DESCRIPTION

FIG. 1 is a front perspective view of a first embodiment of a hitch and customizable rectangular hitch cover combination showing my new design;

FIG. 2 is a top rear perspective view thereof;

FIG. 3 is a bottom rear perspective view thereof;

FIG. 4 is a front perspective view of a second embodiment of a hitch and customizable rectangular hitch cover combination showing my new design;

FIG. 5 is a top rear perspective view thereof;

FIG. 6 is a bottom rear perspective view thereof;

FIG. 7 is a front perspective view of the customizable rectangular hitch cover of both embodiments of the hitch and customizable rectangular hitch cover combination shown separately for ease of disclosure only;

FIG. 8 is a front elevation view thereof;

FIG. 9 is a rear elevation view thereof;

FIG. 10 is a right side elevation view thereof;

FIG. 11 is a left side elevation view thereof;

FIG. 12 is a top plan view thereof; and,

FIG. 13 is a bottom plan view thereof.
